UNITED STATES PATENT OFFICE.

HERBERT E. SMITH, OF SPOKANE, WASHINGTON.

MAIL-EXCHANGING DEVICE.

1,276,280.

Specification of Letters Patent. Patented Aug. 20, 1918.

Application filed December 27, 1916. Serial No. 139,120.

To all whom it may concern:

Be it known that I, HERBERT E. SMITH, a citizen of the United States, residing at Spokane, in the county of Spokane and State of Washington, have invented certain new and useful Improvements in Mail-Exchanging Devices, of which the following is a specification.

My invention relates to improvements in mail exchanging devices for the transfer-
10 ence of mail pouches from a moving train to a receiving and delivery station or from such station to a moving train.

The improvements involved are closely allied with the apparatus set forth in my co-pending application for patent for mail exchanging devices, filed August 29, 1916, Serial Number 117,447, in that certain portions or elements common to both, are quite 20 similar in construction and mode of operation.

The principal object of the present invention is to simplify the construction of my previous device as a whole and to improve 25 the details of construction of certain of the essential elements.

More generally, another object of my invention is the provision of a device of the foregoing character by means of which general mail matter, including parcel post 30 matter, can be safely transferred from a moving train, traveling at high speed, to a station, or vice versa, without danger of injury to the operators, the contents of the 35 mail bags, or to the exchanging apparatus itself.

A further general object of my invention resides in the provision of an apparatus to effect the foregoing exchanges, which also 40 includes in its organization means by which both of said operations—the transference from the train to the station and from the station of the train—may be performed practically simultaneously; that is, a mail 45 car equipped with my apparatus, in passing a station will not only take up the mail from the station, but will also, at substantially the same instant, serve to transfer other mail to the station.

50 In accomplishing my purpose I have provided a greatly improved mechanism for maintaining the mail bag catcher and supporting arms in their extended operative position, and also simplified the device by 55 eliminating the vertically pivoted bag sup-

porting members of the station apparatus such as disclosed in said copending application. Otherwise the operation of the two inventions is substantially the same and I will therefore, and to avoid confusion and 60 prolixity, illustrate and describe only such elements of an exchanging device as will enable me to clearly set forth the construction, operation and advantages of my improve-
ments.

65 In the accompanying drawings—

Figure 1 is a view of the station apparatus as viewed from the direction of the railway and showing a mail bag held by the catcher hooks and the catcher arms 70 swung into the position they would assume immediately after a bag catching operation.

Fig. 2 is an endwise view illustrating the relative positions of the station and car apparatus at the moment of exchange, the 75 arms of the former being extended outwardly and supporting a bag ready for delivery, and the car device arms in extended bag catching position.

Fig. 3 is an enlarged detailed perspective 80 view showing the relative positions of the upper station and car apparatus bag suspending and catcher hooks and indicating a bag supported by the station device ready to be caught by the car hooks.

Fig. 4 is an enlarged bottom plan view of 85 my improved shock absorber and the co-acting mechanism for positioning and maintaining the arms of the station apparatus in desired operative and inoperative positions, 90 the several parts being shown in their relative positions when the catcher and bag supporting arms are swung inwardly out of operative position.

Fig. 5 is an enlarged side elevation of 95 said device with the members in inoperative positions, and

Fig. 6 is a different side view in elevation thereof.

Referring more particularly to the drawings in which like reference characters are used to indicate like parts in the several views, the numeral 1 designates the upright arm supporting standard which is revolu-
100 bly mounted at either extremity in bearings 2 of the station structure. This structure is preferably built up of metallic tubing 3 and elbow fittings 4, and is adapted to support by means of the brackets 5 a platform 105 6. The lower legs 7 of the structure are 110

preferably tapered as shown and anchored to suitable foundations 8. Steps 9 secured to said legs afford easy access to the platform.

- 5 The upper arm 10 and the lower arm 10' are mounted on the standard 1 at right angles thereto and held rigid by means of the braces 11. As shown in Figs. 1 and 3 these arms 10 and 10' carry at their free ends bag catching hooks 12 and 12' respectively which may be of duplex design as shown for the purpose of serving in their bag catching capacity for trains passing in either direction.
- 10 15 The lower arm 10' is also provided with an extension 13 which carries a bag retaining device 14, as in Fig. 2, while on the upper arm 10 is mounted a bag supporting goose-neck 15 having a bag retaining device 16, 20 clearly shown in Fig. 3.

As illustrated in Figs. 2 and 3 the mail bag pouch which the contrivance just described is designed to suspend for catching by the apparatus of a passing train in motion, is provided at either end with flexible lines 17 having at their extremities conically shaped buffer members 18 which are adapted to engage the bag retaining devices 14 and 16, in a manner to allow of instantaneous 25 removal therefrom of the bag upon impact of the catcher hooks or devices of the train apparatus with the lines 17, as indicated in Fig. 2.

In effecting a transference to a car the bag supporting arms 10, 10' of the station apparatus are extended outwardly from the structure in the direction of the railway as shown in Fig. 2, and as it is essential to provide means for steadyng or stabilizing 40 and maintaining the arms in such position so that they will not be dislodged prematurely by wind, train suction, or other untoward conditions, I have provided an improved and novel device to satisfactorily 45 accomplish this purpose and also, in connection therewith, a shock absorbing mechanism to take up the shock incident to the bag exchanging operation.

This retaining and shock absorbing device 50 is mounted upon the lower extremity of the revoluble standard 1 and consists of the substantially U-shaped angle bracket 19 one end of which is fixedly mounted upon the lower end of said standard 1 at 20. 55 Disposed between the legs 21 and 21' of the bracket 19 and having one end supported thereby, is the air compression cylinder 22, the head end thereof being pivotally mounted at 24 to the bolt 25 carried by the bracket 19. The lower leg 21' of the bracket 60 is of somewhat greater length than the upper leg 21 and has mounted at its extremity a grooved wheel 26.

The outer end of the piston rod 27 of 65 the cylinder 22 is pivotally mounted at 28

upon the shaft 29 which is suitably fixed to the floor or platform 6 by bolts 30 and depends therefrom. A coil spring 31 has its opposite ends secured to the lower end of said shaft 29 and at 31' to the extended leg 70 21' of the bracket 19 intermediate of its length.

Bolted to the platform 6 subjacent thereto is the L-shaped angle piece 32 which carries the spring controlled latch device clearly 75 illustrated in Figs. 4 and 6. This latch device is composed of the slidably mounted arcuate segmental member 33 provided with the curved recess 34, the member 33 being under tension of the spring 35.

Upon manually positioning the mail bag supporting and catching arms in their outward operative position the grooved wheel will engage the latch member 33 and serve to lock the mechanism in its set position, at 85 which time the spring 31 will be positioned so as to exert tension from its point of connection 31' on leg 21' through the axis of the movable standard 1 to which the upper leg 21 of the bracket 19 is fixedly secured 90 and its point of connection to the stationary shaft 29. This will be clearly manifest from the view, Fig. 4.

Assuming that the mechanism has been "set" in its operative position, a sudden 95 shock, such as that imparted by impact of the catcher devices of the car apparatus, will serve to roll the wheel 26 out of the recess 34 and allow the rest of the mechanism free action under tension of spring 100 31 to return the arms rearwardly. The latch member 33 being under tension of the spring 35 will normally position itself somewhat forwardly of the point it will assume when engaging the wheel 26, as in 105 the latter instance the spring is compressed and acts directly upon the wheel to lock the two parts together. To release the wheel a sudden shock or impact of considerable force is necessary, and the latch will resist 110 effectively such dead pull as might result from wind or train suction.

Referring now particularly to Fig. 2 of the drawings it will be noted that the upper bag supporting gooseneck 15 of the station 115 apparatus is superposed with relation to the catcher hooks 12' and also upon a higher relative plane than the upper bag supporting arm 36 of the train device; and that the lower bag supporting device 14 of the station apparatus extends outwardly from and in substantially the same plane as the lower catcher hooks 12'. Also, that both the lower bag catcher hooks 37 and the bag supporting device 38 on the arm 39 of the train apparatus are above the plane of the corresponding station hooks and supporting device.

The lower bag support 38 and the upper bag support 40 of the train apparatus, it should be noted, are merely extensions of 130

the bag hooks 37 and 41 and are in substantially the same planes as their respective hooks.

This arrangement and relative disposition 5 of the catcher and supporting devices is of the utmost importance, as I am thereby enabled to use either apparatus for both catching and delivery of the mail bags or for the simultaneous exchange of two bags, 10 one from the car to the station and the other from the station to the car. And I will claim such arrangement and disposition as a distinct feature of my invention.

The function and operation of the shock 15 absorbing cylinder are obvious. Such mechanism is included in my previous application for patent already herein referred to and, aside from its coöperation with the other elements of the mechanism for maintaining 20 the bag supporting arms in extended position, and returning and retaining said arms in inoperative position, forms or constitutes in itself no part of my claims to invention in this case.

25 It is to be understood that the train apparatus is preferably controlled, as regards maintenance of the arms in outward position and absorption of shock, by means of mechanism substantially similar to that disclosed 30 in said co-pending application, and I do not lay claim to such mechanism herein.

Pivotal swinging movement of the arms to accommodate trains passing in either direction is provided for by my novel mechanism 35 and any danger of damage or destruction thereof by a passing apparatus improperly set, is obviated.

Having described my invention, I claim:—

1. In a device of the character described, 40 a supporting structure, a revoluble standard mounted thereon, arms carried by said standard, a tensionally controlled member carried by said standard, an engaging device carried by said member, a stationary spring controlled recessed latch adapted to coöperate 45 with said engaging device to retain said arms in predetermined operative position, and a spring having one end secured to said tensionally controlled member for exerting tension thereon and for returning 50 and retaining said arms in their inoperative position.

2. In a device of the character described, 55 a stationary mail bag supporting structure having horizontally extended upper and lower bag supporting and bag catching

arms, bag catching hooks carried by said arms, a superposed bag supporting device disposed above the plane of said upper arm, and a bag supporting device carried by said 60 lower arm, said hooks and supporting devices being adapted for coöperation with a car apparatus to effect the transference of mail bags from the car to the station and vice versa.

3. In a device of the character described, a supporting structure, a revoluble standard mounted thereon, arms carried by said standard, a spring controlled substantially 70 U-shaped bracket having an upper and an extended lower leg, the former being fixedly mounted upon said standard, an engaging device carried by said lower leg; a stationary latch adapted to engage said engaging device to retain said arms in predetermined operative position, a spring having one end secured to said lower leg for exerting tension thereon and for returning and retaining 75 said arms in their inoperative position; a shock absorbing fluid compression cylinder 80 having one end secured to said bracket and a piston coöoperating therewith having the free end of its rod pivotally mounted, said spring and shock absorbing device coöperating to maintain said arms in operative 85 position, absorb shocks, and to balance the elements of the apparatus during the mail bag exchanging operation.

4. The combination with a supporting structure, a revoluble standard, and mail bag 90 supporting means on the standard, of a retaining bracket fixed to the standard, a fluid pressure cylinder pivoted to the bracket and a piston stem therefor pivoted to a post on the supporting structure, a contractile 95 spring suspended between said post and bracket, and means for retaining the bracket and cylinder in alined position.

5. The combination with a supporting structure, a revoluble standard and mail bag 100 supporting means thereon, of a U-shaped retaining bracket fixed to the standard, a fluid pressure cylinder pivoted to the bracket and to a post on the supporting structure, a contractile spring suspended between the bracket and post, a roller on the free end of the bracket, a latch bracket on the structure, and a latch member resiliently supported by said bracket for coöperation 105 with the roller.

In testimony whereof I affix my signature.
HERBERT E. SMITH.
